UNITED STATES PATENT OFFICE

90,893

DESIGN FOR A BUILDING

Robert W. McLaughlin, Jr., New York, N. Y., assignor to American Houses, Inc., New York, N. Y., a corporation of Delaware

Application May 23, 1933. Serial No. 48,195

Term of patent 14 years

To all whom it may concern:

Be it known that I, ROBERT W. McLAUGHLIN, JR., a citizen of the United States, residing at New York, in the county and State of New York, have invented a new, original, and ornamental Design for a Building, of which the following is a specification, reference being had to the accompanying drawings, forming part thereof.

Fig. 2 is a perspective view of a detail of said building.

The device shown in the drawings is made and sold as a complete article of manufacture.

In each figure the dominant features of the design have been shown in full lines.

I claim:

The ornamental design for a building as shown and described.

ROBERT W. McLAUGHLIN, JR.
